UNITED STATES PATENT OFFICE.

HELON B. MACFARLAND, OF CHICAGO, ILLINOIS.

DRAFT-INDUCING MEANS FOR LOCOMOTIVES AND THE LIKE.

1,125,361.

Specification of Letters Patent.

Patented Jan. 19, 1915.

Application filed December 20, 1913. Serial No. 807,893.

To all whom it may concern:

Be it known that I, HELON B. MACFARLAND, a citizen of the United States, and resident of Chicago, county of Cook, and 5 State of Illinois, have invented certain new and useful Improvements in Draft-Inducing Means for Locomotives and the like, of which the following is a description, reference being had to the accompanying drawings, which form a part of my specification.

My invention relates to means for mechanically inducing the draft in a locomotive; and has for its object the provision of a construction whereby the draft inducing 15 means will be automatically controlled, so that the draft induced will be commensurate with service conditions, thus resulting in a locomotive wherein combustion is more economically induced than is the case with 20 constructions as heretofore employed.

A further object of the invention is the provision of draft inducing means which will be at all times under the regulation and control of the engineer; and wherein the exhaust steam from the steam chests of the 25 cylinders will be unrestrictedly discharged into the atmosphere, so that the back pressure heretofore encountered will be eliminated; the advantages of my improved construction being readily apparent from the 30 following detailed description.

In the drawings:—Figure 1 is a longitudinal sectional view and partial side elevation of the front or smoke-box end of a locomotive, illustrating my invention in side elevation; with only a portion of a steam chest and cylinder being shown, and a portion of the exhaust steam conveying means being broken away, while the remainder is 35 shown in section. Fig. 2 is a side elevation of the fire-box end of the locomotive with the cab shown in section; the engine and trucks being omitted in the different figures. Fig. 3 is a longitudinal sectional view and 40 partial side elevation of the smoke-box end of a locomotive, showing my invention applied to a locomotive using saturated steam. Fig. 4 is a front elevation of Fig. 3, with the front head removed and the saddle casting 45 broken away.

In the particular exemplification of my invention, it is shown in Fig. 1 applied to a common type of construction of simple locomotive provided with a well known type of

superheater; the invention, however, being 55 adapted for use in connection with the various types of locomotives, with or without superheaters.

The improved means is more especially intended to be located in the smoke-box 60 forward of the flue-sheet 6 of the boiler 7, which latter is partially shown in section, in Fig. 1, with the rear or fire-box end thereof being shown in side elevation in Fig. 2, wherein the cab 8 is shown in partial section. The steam-dome 9 is provided with the usual throttle at 10 whereby the passage of steam into the dry steam pipe 11 is controlled. The steam is led by means of pipe 11 into the rear chamber 12 of the superheater, from whence it is led by means of a series of pipes 13 rearward into the enlarged fire-flues 14 and thence forward into the forward chamber 15 of the superheater by means of the return pipe 16. The superheated steam is then led by means of conduits or steam-pipes 17 to the steam-chests of the cylinders on both sides of the locomotive in the usual well known manner.

In the construction illustrated, the smoke-box 5 is provided with a partition 18 located forward of the superheater, and, therefore, forward of the front ends of the fire-flues; the partition 18 being secured to the smoke-box shell so as to make an air tight compartment. The partition 18 is provided with a suitable opening, arranged at the desired place, which is provided with the tapering or approximately frusto-conical shell 19 which latter registers with the intake point of a suitable blower or fan rotatably mounted in the shell or casing 20. The blower communicates with the smoke-stack 21 by means of the delivery conduit 22; the blower causing a peripheral discharge of the gases into the stack 21.

The fan or blower is shown driven by a steam turbine, which may be of a well known type, located in the casing 23 and preferably forward of the blower, being 90 directly connected with the fan or blower as in the construction set forth in my previous Patent No. 1,059,378, of April 22, 1913.

The driving means or turbine in my improved construction is arranged to receive 105 live steam by means of separate conduits, both of which are under control of the engineer and are adapted to be independently

used as will very clearly appear in the following description.

In the particular construction shown, a conduit 24 is provided for conveying steam to the turbine or driving means 23; the conduit 24 being preferably located to the outside of the boiler shell, leading rearwardly to the cab of the locomotive and conducting live steam from any suitable point in the steam spaces of the boiler. I have chosen to show the conduit 24 connecting with a steam fountain 25, see Fig. 2, and also provided with a valve 26 located at any suitable point in the cab of the locomotive whereby the flow of steam through the conduit may be controlled by the engineer.

At a suitable point intermediate of the driving means or turbine and the valve 26, the conduit or line 24 is provided with a suitable connection 27 provided with a cut-out or valve 28. The connection 27 permits the conduit 24 to be connected with a live steam or compressed air line in the round house while the locomotive is being fired, previous to the generation of steam.

At a point in advance of the point of delivery of steam conduit 24 to the driving means or turbine 23, the conduit or line is provided with a suitable check valve as at 29, whereby the flow of steam to the driving means may be automatically controlled.

Intermediate of the checking valve 29 and connection 27, I show the conduit or line 24 provided with a suitable valve 30; and located in advance thereof, relative to the travel of steam, the line 24 is provided with the auxiliary draft inducing means or blower 31 which is provided with a suitable valve 32. The valve 32 controls the passage of steam through the auxiliary blower line 31, which may be operated in any desired manner. With valve 32 closed steam will not be passing through blower line 31 under normal conditions; the blower line being especially intended for use when the mechanical draft inducing means is inoperative.

The steam line or conduit 24 conveys the steam to the driving means or turbine 23 by means of the connection 33; and the exhaust steam from the turbine is conveyed by pipe or conduit 34 into the atmosphere in any suitable manner; for example the pipe 34 may be arranged to discharge the steam into the stack 21 as shown in Fig. 1.

The exhaust steam from the steam chests of the cylinders is freely delivered into the atmosphere by means of suitable pipes or conduits, as for example by exhaust pipes 35, which are shown extending about the outside of the boiler shell and terminate in a single delivery end 35^a at a point forward of the smoke stack 21. The method of conveying the exhaust steam from the steam chests of the cylinders illustrates a con-

venient manner of accomplishing the purpose, but it is readily apparent that the conduits may be differently arranged without, however, causing any back pressure.

In addition to the live steam line 24 whereby steam for operating turbine 23 is provided, I provide a line or conduit 36 which connects with the connection 33 and is adapted to supply steam to the driving means or turbine only when the throttle has been opened. The line or conduit 36 in the particular construction illustrated, is shown connected with the forward or superheated steam compartment 15 of the superheater, so that steam will only flow through conduit 36 after the throttle has been opened to allow steam to pass through pipe 11 from the steam dome of the boiler and into the superheater. In order that the flow of steam through conduit 36 may be shut off when desired, I show the conduit provided with a suitable valve as at 37, which may either be operable from the outside of the boiler-shell, or through the door in the front head of the smoke box, as under ordinary conditions valve 37 would remain open; again this valve may be arranged to be operable from the cab of the locomotive. The steam line 36 is also provided with a suitable check valve 38, which, like valve 29, will prevent the backing up of steam from line 36 into line 24 or vice-versa. The valves 29 and 38 may be so constructed as to automatically close when steam is admitted either into conduit 24 or conduit 36. For example, with valve 29 arranged to automatically close under the conditions just recited, it will positively prevent the passage of saturated steam from line 24 when the locomotive is working superheated steam; while the automatic closing of valve 38 will prevent the passage of superheated steam when the locomotive is working saturated steam, thereby greatly increasing the economy of operation of the driving means or steam turbine 23. The valves 29 and 38 are illustrated as simple, separate check valves of proper size, although it would be possible to combine these features into a comparatively compact self-contained fitting which may be conveniently attached to the turbine inlet.

Intermediate of the connection 33 and the driving means or turbine 23, I provide a pressure regulating governor 39 possessing the function of automatically shutting off the steam supply to the driving means or turbine when a maximum pressure has been obtained, so that the draft or pull on the fire will be reduced and the locomotive prevented from wasting steam through the safety valves. The governor 39 is provided with the line 40 which communicates with the steam space of the boiler in any convenient manner; in the illustration in Fig. 1

1, this line is shown extending to and secured in the front flue-sheet of the boiler at a point above the dry steam pipe 11.

The operation of my invention is as follows:—assuming that the locomotive is “cold” and standing in the round house, in order to fire up and get the locomotive in readiness for the road, connection is made with the round house blower line, by means 5 of connection 27, and valve 28 opened, while valve 26 in the rear end of line 24, is closed; and valve 30 so operated as to permit the steam from the round house line or air to pass through line 24 and the driving 10 means or turbine 23; or through the auxiliary blower 31 which is accomplished by opening valve 32 and closing valve 30. As soon as sufficient pressure is available, it is preferable to set the turbine in operation 15 on account of the blower or fan 20 possessing greater efficiency than auxiliary blower 31. When the turbine is brought into operation, the valve 29 will permit a free flow of steam or air into the turbine, or driving 20 means 23, while valve 38, however, will automatically close and prevent the backing up of steam into the superheater, (in the particular type of locomotive shown) or into the dry pipe and connecting conduits 25 which lead to the steam-chests of the cylinders, as that would result in a very objectionable construction. After a sufficient head of steam has been raised in the locomotive-boiler, the connection at 27 is broken, valve 30 30 closed, and steam supplied by means of pipe 24 from fountain 25, through the opening of valve 26. As soon as a full head of steam has been obtained, valve 26 is either partially or wholly closed, so that 35 the driving means or turbine 23 will either operate at a very slow or greatly reduced speed or entirely stop. With the locomotive ready to move out of the round-house, the main locomotive throttle is then opened and 40 steam admitted into the dry pipe or conduit 11, and in turn into the superheater chambers 12 and 15 successively, and thence into conduit 36. The admission of the steam into conduit 36 will move or open valve 38 45 and permit the steam to enter connection 33 and be delivered to the driving means or turbine 23. The admission of steam beyond check valve 38 will induce check valve 29 to close and thus prevent the steam backing 50 up into conduit 24. Through the opening of the throttle, therefore, the turbine 23 is started either at full or partial speed depending upon the pressure in the superheater chamber or header 15, in the construction 55 illustrated in Fig. 1, or upon the pressure in the dry pipe 11 where the locomotive employs saturated steam as illustrated in Fig. 3. It is apparent therefore 60 that the opening of the throttle will start the 65 fan or blower 20 and consequently induce

a draft through the boiler and increase the action upon the fire correspondingly.

With my improved construction, if the flow of steam through conduit 36 is of such volume as to cause the turbine to operate 70 at such speed so as to produce draft causing a higher rate of consumption than is required to generate sufficient steam for the operation of the locomotive, resulting in the boiler pressure reaching popping off 75 point, the governor mechanism 39 will automatically close off the steam supply to the driving means or turbine 23. The motive power for the blower or fan having been shut off, it is evident that the draft or 80 pull on the fire will be decreased and thus prevent the locomotive from popping off.

If, during the operation of the locomotive, the pressure in the superheater chamber 15 should fall below the pressure necessary to 85 operate driving means or turbine 23 at full speed, and it is still necessary to maintain that full speed, the valve 26 may be opened allowing steam to flow from the steam space of the boiler or from fountain 25, in the 90 construction illustrated. The steam flowing through conduit 24 will open check valve 29 because of the greater pressure upon the under side thereof in view of the reduced 95 pressure obtained through the flow of steam through conduit 36. Steam, therefore, will be allowed to flow to the turbine 23 from conduit 24 and supplement the steam entering through conduit 36 and thereby operate the turbine at a greater speed, consequently 100 inducing a higher rate of combustion, resulting in the generation of sufficient steam to build up the falling boiler pressure.

As is clearly evident from the construction shown and described, when it is desired 105 to stop the locomotive, the main locomotive throttle is closed by the engineer, which in turn will automatically close off the flow of steam to turbine 23 because of the fact that no steam pressure will be obtained in the 110 superheater chamber, or in the dry pipe, thus resulting in the draft inducing means becoming inoperative and necessarily cutting down the draft and consequent pull on the fire, thereby reducing the combustion to 115 a rate commensurate with that of the conditions encountered by the locomotive. If it should be still desired to build up the fire, valve 26 may be opened and blower or fan 20 operated either at full or partial 120 speed to meet the requirements.

In Figs. 3 and 4, I show the application of my invention to a locomotive employing saturated steam, so that the line or conduit 36^a connects with the dry pipe 11^a, or with 125 the T head 41 with which the conduit 17^a connects, whereby the steam is led to the steam chests of the cylinders. As the superheater is not employed, the fire flues 14^a are of the usual construction and if desired the 130

partition 18^a may be brought closer to the fire-flues; the partition being provided with an opening which communicates with the blower or fan 20^a, as in the previously described construction; the fan or blower being operated by the turbine or motor 23^a directly connected thereto as in the previously shown construction. The motor or turbine receives the steam either by means of line 24^a which extends backward to the cab of the locomotive and communicates with the steam space of the boiler or with a fountain as shown at 25 in Fig. 2; this line being provided with the cut-off or valve 30^a and with the connection 27^a; or the turbine receives steam by means of line 36^a which latter has a cut-off or valve 37^a. Both lines 24^a and 36^a are provided with the check valves 29^a and 38^a. As in the previously shown construction, I provide the regulating governor 39^a whereby the maximum pressure in the boiler will automatically control the steam supply for the turbine. As previously described, it is evident that if steam is not flowing through conduit 24^a, the blower or fan will only be in operation when the throttle of the locomotive is open, thereby admitting steam from the steam dome of the locomotive into dry pipe 11^a from whence it flows by means of conduit 36^a to the turbine. This condition will be maintained unless the boiler pressure reaches popping off point, in which event the governor will automatically shut off the flow of steam from conduit or line 26^a to the turbine and hence stop the operation of the fan or blower and thereby decrease the draft or pull upon the fire.

I have shown and described my invention in connection with several types of locomotives, but it will be understood that the invention may be readily adapted for general service on any class of locomotive or steam generator, and the constructions illustrated and described may be modified in certain details without, however, departing from the spirit of my invention, and I do not wish to be understood, therefore, as limiting myself to the exact constructions shown and described.

What I claim is:—

1. Draft inducing means for a locomotive having a boiler provided with a smoke-stack and a throttle, comprising means communicating with the smoke stack whereby draft is mechanically induced, and means intermediate of the throttle and said first mentioned means whereby the latter is automatically operated when the throttle is opened.
2. Draft inducing means for a locomotive having a boiler provided with a smoke-stack and a throttle, comprising means communicating with the smoke stack whereby draft is mechanically induced, means intermediate of the throttle and the first mentioned

means whereby the latter is automatically operated when the throttle is opened, and means whereby the first mentioned means is controlled when the boiler pressure reaches a predetermined degree.

3. Draft inducing means for a locomotive provided with a smoke-stack, a cab and a throttle, comprising means communicating with the smoke stack whereby draft is mechanically induced, means operable from the cab of the locomotive whereby steam is supplied to said first mentioned means, and means whereby steam is supplied to the first mentioned means when the throttle of the locomotive is opened.

4. Draft inducing means for a locomotive provided with a smoke-stack and a throttle comprising means communicating with the smoke stack whereby draft is mechanically induced, a pipe line adapted to receive an operating medium from a source of supply, and a second line intermediate of the throttle and the first mentioned means whereby steam is supplied to the latter independently of said first mentioned pipe line.

5. Draft inducing means for a locomotive provided with a smoke-stack and a throttle comprising means communicating with the smoke stack whereby draft is mechanically induced, a pipe line adapted to receive steam or other operating medium from a source of supply and arranged to deliver it to the first mentioned means, a second line intermediate of the throttle and the first mentioned means whereby the latter is supplied with steam when the throttle is opened, and means located in said lines whereby flow of the steam or operating medium from one line into the other is prevented.

6. Draft inducing means for a locomotive provided with a smoke-stack and a throttle comprising means communicating with the smoke stack whereby draft is mechanically induced, a pipe line adapted to receive steam or other operating medium from a source of supply and to operate said first mentioned means, a second line intermediate of the throttle and the first mentioned means whereby steam is supplied to the latter when the throttle is opened, and means whereby the first mentioned means is controlled when the boiler pressure reaches a predetermined degree.

7. Draft inducing means for a locomotive provided with a smoke-stack and a throttle comprising means communicating with the smoke stack whereby draft is mechanically induced, a pipe line adapted to receive steam or other operating medium from a source of supply to operate the first mentioned means, a second line intermediate of the throttle and the first mentioned means whereby steam is supplied to the latter when the throttle is opened, means located in said lines whereby flow of steam or other operat-

ing medium from one line into the other is prevented, and means whereby the first mentioned means is automatically controlled when the boiler pressure reaches a predetermined degree.

- 5 8. In draft inducing means for a locomotive provided with a boiler having fire-flues, a smoke-stack and a throttle, the combination of a smoke-box or chamber forward of the fire flues of the boiler of the locomotive, driving means arranged in said chamber, and draft inducing mechanism directly connected with said driving means and in communication with the smoke stack, the suction end of said mechanism communicating with the forward ends of the fire flues of the boiler of the locomotive, with a pipe line adapted to receive steam or other operating medium from a source of supply, and a second pipe line intermediate of the throttle of the locomotive and the driving means whereby steam will be supplied to the latter when the throttle is opened.

9. In draft inducing means for a locomotive having a boiler provided with fire-flues and a throttle, the combination of means located forward of the fire flues of the boiler of the locomotive whereby draft is mechanically induced, with a pair of lines adapted to convey steam to said means to operate the same, one of the lines communicating with the steam space of the boiler while the other communicates with the steam supply obtained through operation of the locomotive throttle, and means for automatically determining the line adapted to supply the steam for operating said draft inducing means.

10. In draft inducing means for a locomotive provided with a boiler having fire-flues and a throttle, the combination of means located forward of the fire flues of the boiler adapted to mechanically induce draft through the fire flues of the boiler, a pair of lines adapted to convey steam to said means to operate the same, one of the lines communicating with the steam space of the boiler while the other communicates with the steam supply obtained through operation of the locomotive throttle, and means for automatically determining the line adapted to supply the steam for operating said draft inducing means.

11. In draft inducing means for a locomotive having a boiler provided with fire-flues and a throttle, the combination of means located forward of the fire flues of the boiler for mechanically inducing draft, and a pair of lines adapted to convey steam to said means to operate the same, one of the lines communicating with the steam space of the boiler, while the other communicates with the steam supply obtained

through operation of the locomotive throttle, with means arranged to be controlled by the boiler pressure and adapted to automatically control the steam supply for said draft inducing means.

12. In draft inducing means for a locomotive having a boiler with fire-flues and an auxiliary blower, the combination of means located forward of the fire flues of the boiler adapted to mechanically induce draft, with a pair of lines adapted to convey steam to said means to operate the same, one of said lines communicating with the steam space of the boiler and adapted to supply steam to the auxiliary blower of the locomotive, and means whereby the direction of flow through said lines is controlled.

13. In draft inducing means for a locomotive provided with a boiler having fire-flues and a throttle, the combination of means located forward of the fire flues of the boiler for mechanically inducing draft therein, with a pair of lines adapted to convey steam to said means to operate the same, one of said lines communicating with the steam space of the boiler and arranged to receive steam or other operating medium from an extraneous source while the other line communicates with the steam supply obtained through operation of the locomotive throttle, and means for independently controlling the flow through said lines.

14. Draft inducing means for a locomotive provided with a boiler having fire-flues and a throttle, comprising means located forward of the fire flues for mechanically inducing draft therein, a pair of lines adapted to convey steam to said means to operate the same, one of said lines communicating with the steam space of the boiler and arranged to receive steam or other operating medium from an extraneous source while the other line communicates with the steam supply obtained through operation of the locomotive throttle, and means whereby the steam supply for said draft inducing means will be automatically shut off when the boiler pressure reaches a predetermined degree.

15. Draft inducing means for a locomotive provided with a boiler having fire-flues and a throttle, comprising means located forward of the fire flues of the boiler for mechanically inducing draft therein, a pair of lines adapted to convey steam to said means to operate the same, one of the lines communicating with the steam space of the boiler and arranged to receive steam or other operating medium from an extraneous source while the other line communicates with the steam supply obtained through operation of the locomotive throttle, means for automatically determining the line adapted to supply the steam for operating said draft inducing means, and
